(57) **CLAIM**

The ornamental design for a spice rack, as shown and described.

DESCRIPTION

FIG. 1 is a front, right, and top perspective view of a spice rack showing our new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another front, right, and top perspective view thereof, where the spice rack is shown in an alternate configuration of use.

The broken lines in the drawings depict portions of the spice rack and form no part of the claimed design.

1 Claim, 9 Drawing Sheets
